Application October 22, 1932, Serial No. 639,095
In Germany November 2, 1931

2 Claims. (Cl. 34—19)

The present invention relates to a process for drying material, which comprises exposing the material to be dried to the action of a current of air or another gas, the drying process being performed in a room subjected to periodical changes of the pressure of air or gas, and an apparatus for executing this process.

In most of the drying installations to be used in industry, such as drying chambers with circulating air, roller driers, driers provided with mechanical conveying installations, the drying effect is based upon the fact that the moist air, produced at the surface of the material to be dried due to the evaporation or vaporization, is absorbed by the not completely saturated part of the air and then eliminated, and that the moisture contained within the material gradually follows due to the porosity and diffusing action of the material. Hence it results that the effective rate of decrease in diffusion, which by itself is very small, is not supported by any convective transversal motion of air within the material. The long drying periods are due to these facts.

I have now found that the drying process can be accelerated and the period of drying be shortened by subjecting the air or another gas in the drying apparatus to periodical fluctuations in pressure, thus causing within the pores of the material to be dried a quick change of air or the other gas. This process can be applied in all drying apparatus operating with or without circulating air. The fluctuations of pressure may, for instance, be produced by any air conveying installation. If the drying is performed by means of circulating air, the fluctuations may be produced by a mechanically operating shut-off device which is inserted into the circulating current of air. This shut-off device may also have the form of a revolving flap. The ventilation in the drying chambers may be performed by mechanically controlled means which are suitably adjusted in such a manner that the pulsating action in the drying room is increased thereby.

A particular advantage of the invention resides in the fact that the usual apparatus, the construction of which need not be strengthened, are sufficient, if the pulsations are within the scope of some hundred millimeters of water column. The period of drying can be considerably shortened therewith. The present invention is, however, not limited to these pressure intervals.

In the accompanying drawing a drying apparatus according to the invention is diagrammatically illustrated by a cross section of the device. In the drawing A is a usual drying room with

circulating air, subdivided by the partition M into the two chambers B and G. B is the chamber into which the car C provided with plates for the reception of the material to be dried is introduced. A ventilator D is placed within the heating chamber G, the plane of revolution of the ventilator is between the two air changing flaps K and L and the two openings N and O in the partition M. This ventilator moves the air in the direction of the arrow, the air being heated by the heating device E. At a suitable place a revolving flap F is mounted, which periodically interrupts the circulating current of air. If the flap F is in the situation (1) marked by broken lines, the usual circulation of air takes place. In situation (2), i. e. if the flap F is shut, the ventilator reduces the atmospheric pressure in the room B to an extent which is determined by the size of the rooms in front of and behind the ventilator, its speed and its efficiency. At the same time the pressure in the chamber G increases, this being, however, without any importance for the manner of action of the apparatus. On account of the decreasing pressure in the chamber B, the air charged with moisture leaves the capillaries and cavities of the material to be dried until the reduced pressure has been compensated. The flap F then opens again, the pressure in the chamber B increases and new heated air penetrates from the outside into the pores of the material to be dried so that they are filled up again. The operation is then continuously repeated. In order to attain the desired purpose, it may be advisable to cause the flap to revolve in an irregular velocity in order to control the two periods. A stop device causing the flap to stop in certain positions for a short time may also be used. It may be important to cause the flap to open slowly so that the over-pressure in the chamber G is not compensated too quickly, thus causing a strong current of air to pass over the drying plates, by which current fine material on the plates, for instance dyestuffs, might be blown away. Instead of one flap there may be used several flaps or sliding members, valves and similar devices.

The openings through which the air or another drying gas is introduced into and removed from the drying apparatus may be fitted so that they are controlled by flaps which likewise rotate, thereby increasing the action of pulsation. For instance, in the drying apparatus illustrated in the accompanying drawing the flap K for removing the air may be opened during the whole time or a part of the time when the flap F is shut.

and may cause the air to leave the chamber G in order to change the air. The back-pressure of the ventilator thus decreases at the same time, and the effective vacuum in chamber B increases correspondingly. Through the flap L which likewise operates mechanically air may be introduced into the drying apparatus.

In all other driers filled with air the effect above described is fundamentally the same.

10 It is understood that instead of air another gas, for instance nitrogen or carbonic acid, may also be used as the drying agent.

15 In the following claims by the term "gas" there is to be understood any gas, especially air, nitrogen or carbonic acid.

I claim:

1. An apparatus for drying material, which comprises an air-tight room subdivided into two chambers by means of a partition provided with two openings, a heating device for drying the air, two air changing flaps through which air may be introduced into and removed from one of these

chambers, a ventilator within the same chamber, the plane of revolution of the ventilator being between the two air changing flaps and the two openings in the partition, and a rotating flap closing one of the two openings in the partition and being provided with a device for alternately opening and shutting the flap.

2. An apparatus for drying material, which comprises a gas-tight room subdivided into two chambers by means of a partition provided with two openings, one of said chambers being provided with an inlet and an outlet for the circulating drying gas, a ventilator located in said chamber between said inlet and outlet and between said openings in the partition, a heating device located in said chamber between said inlet and the opening in the partition which is situated on the same side of the ventilator and a device for alternately opening and shutting this opening.
